UNITED STATES PATENT OFFICE.

JOHN R. STANTON, OF NEW YORK, N. Y.

DESIGN FOR A CHECK-HOLDER OR INDICATOR.

44,500.

Specification for Design.

Patented Aug. 12, 1913.

Application filed December 10, 1912. Serial No. 736,027. Term of patent 3½ years.

To all whom it may concern:

Be it known that I, JOHN R. STANTON, a citizen of the United States, residing at the borough of Manhattan, in the city, county, and State of New York, have invented a new, original, and ornamental Design for Check-Holders or Indicators, of which the following is a specification, reference being had to the accompanying drawing, forming part hereof.

Figure 1 is a plan view of a check holder or indicator showing my new design, and Fig. 2 is a side or edge view thereof.

Said design includes a dial with time indications thereon, the upper part of said dial having a vertically extending bar centrally disposed and opposite curved arms extending upwardly at both sides of said central bar.

I claim:

The ornamental design for a check holder or indicator, as shown and described.

JOHN R. STANTON.
